ELECTRODYNAMIC SPEAKER

Filed May 17, 1930

UNITED STATES PATENT OFFICE

RUSSELL T. KINGSFORD, OF WYNCOTE, PENNSYLVANIA, ASSIGNOR TO ATWATER KENT MANUFACTURING COMPANY, OF PHILADELPHIA, PENNSYLVANIA, A CORPORATION OF PENNSYLVANIA

ELECTRODYNAMIC SPEAKER

Application filed May 17, 1930. Serial No. 453,130.

My invention relates to telephonic apparatus of the electro-dynamic type, and particularly such as may be utilized as loud speakers either in radio reception or for other purposes.

In accordance with my invention the electro-magnetic field structure comprises a casting or pot having a central core terminating in a pole piece disposed centrally in a circular aperture in an outer pole plate structure which is held, with its aperture concentric with the central pole piece to form an air gap of uniform length, against the end of the pot, whether or not flanged, to prevent its displacement with respect to the core or pole piece without recourse to a spacing ring or other centering means.

Further in accordance with my invention, the outer pole plate structure comprises a pole plate having secured thereto, preferably on the inner side thereof, a second plate, also of magnetizable material, effecting reduction in magnetic reluctance and at the same time cheapening the structure; and more particularly the inner plate approaches the inner pot wall sufficiently closely to reduce magnetic reluctance, while their distance apart may be such that if the outer pole plate structure were shifted, it would at its air gap aperture strike the voice coil, or even the inner pole piece, without the edge of the inner plate reaching or contacting with the inner wall of the pot.

My invention resides in structure and features of the character hereinafter described and claimed.

For an illustration of some of the various forms my structure may take, and for an understanding of the invention in general, reference is to be had to the accompanying drawings, in which:

Fig. 1 is a vertical sectional view of an electro-dynamic loud speaker of the cone type embodying my invention;

Fig. 2 is a side elevational view of my novel pot with its central core;

Fig. 3 is a top plan view of the structure shown in Fig. 2;

Fig. 4 is a bottom plan view of the composite outer pole plate structure;

Fig. 5 is a side elevational view of the structure shown in Fig. 4;

Fig. 6 is a fragmentary view in section, illustrating a modification in which the pot flange is omitted;

Figs. 7 and 8 illustrate the strips from which are procured respectively rectangular and circular blanks for pot formation.

Referring to Figs. 1 to 5 inclusive, P is a casing or pot of magnetic material upon whose bottom 1 is secured the inner core 2, held in fixed and non-adjustable position with respect to the pot by the screw or bolt 3 threaded into the core 2 after passing through the supplemental bottom plate 4 of magnetizable material, utilized when desirable.

Surrounding the core 2 is the field winding C, energized by direct or rectified alternating current, to produce a substantially unfluctuating magnetic field in the air gap between the circular inner pole piece I, on the core 2, and the inner wall of the aperture 5 in the outer pole plate structure O, having adjacent its outer edge holes 6 through which and the flange 7, upon the pot P, extend bolts or screws 8, which securely hold the pole plate structure O fixedly upon the pot P with the aperture 5 truly concentric with the pole piece I, without recourse to or need for a spacing or centering ring or disc or other means for locating structure O with respect to pole I.

The plate structure O may be centered with respect to the inner pole I in any suitable way, as by introduction into the air gap of a gauge or gauge elements, and when so centralized the bolts 8, which preferably have substantial clearance in the holes 6, are tightened.

The outer pole plate structure may be unitary, or, and preferably, as indicated, is composite, comprising the larger plate 9 having secured thereto by rivets 10, or equivalent, the smaller and inner plate 11, both plates having registering apertures.

When the parts are in the assembled position described, the coil C is held in place against the bottom washer 12 of insulating material by the upper washer 13 of paste-

board or equivalent material upon which pressure is applied by several blocks or pieces 14 of felt or the like, spaced circumferentially, against which presses the outer pole 5 plate structure O.

The composite outer pole plate structure yields sufficient thickness of magnetizable material to maintain sufficiently low the magnetic reluctance of the circuit, and is at the 10 same time cheaper than a single, thicker structure having the same effect. The curved or circular edges 15 of the inner plate 11 closely approach the inner wall of the pot P, as indicated in Fig. 1, to maintain low 15 magnetic reluctance. Nevertheless, the spacing may be such that in event of displacement of outer pole plate structure O the wall of the aperture 5 would first engage the movable coil S, or even the periphery of the 20 inner pole piece I, before touching the pot P.

The screws 8 also secure to the pot structure the sheet metal housing 16 having suitably large openings 17, and having the outwardly turned circular flange 18 terminating 25 with the forwardly extending flange 19, forming a channel within which is disposed the ring 20 of felt, paper or other suitable material. Upon the washer 20 lies the annular disc 21 of flexible cloth or the like to 30 whose inner flange 22 is attached the outer end of the conical diaphragm D of paper or other suitable material. Overlying the member 21 is a metal ring or washer 23 held by the screws 24.

35 The coil S, traversed by signal- or sound-representing current, is disposed in one or more layers upon the coil form or support F between whose forward ends and the sheet metal flange 25 is held the inwardly turned 40 end 26 of the cone D which overlies the conical flange 27 integral with the flange 25, which in turn is integral with the spring spider Z 45 of aluminum or other suitable material, secured at its center by screw 28 to the lug or projection 29 upon the inner pole piece I.

With the screws 24 loose, the cone D is first centered by means of removable spacers inserted through apertures in spider Z between the inside of the coil form F and the outside 50 of the inner pole piece I, and then by tightening the screw 28 the spider Z is secured to the inner pole piece I, whereupon the screws 24 are tightened with assurance that the cone as a whole is properly positioned 55 or centered.

The voice coil leads L extend from the moving coil system to suitable terminals 30; and the leads 31, 31 from the coil C extend to similarly fixed terminals 32. The terminals 60 are secured upon suitable insulating material mounted upon the housing 16, and enclosed in a metal cap 33, secured to the housing, and having a neck 34 through which extends a cable 35, in which are disposed the 65 four conductors connecting with the two

70 terminals 30 and the two terminals 32 within the cap 33, between whose inner side and the terminals, their mountings and connections may be interposed a paper or other suitable covering 36.

A pot of the character illustrated in Figs. 1, 2 and 3 is drawn to form by a suitable die operating upon an oblong cold blank, such as indicated at B, Fig. 7, stamped or cut from strips of stock 37 having suitable magnetic 75 and die-working properties. Each blank B is substantially longer than its width for producing a pot of the form or proportions indicated in Figs. 2 and 3. In forming the pot, there is left a V-shaped notch N on each 80 of opposite sides, terminating at or in the flanges 7, which, by suitable formation of the die, may have the straight sides 38. After the pot-forming operation, there generally remains a more or less ragged edge 85 around the flange 7 and straight sides 38, which is readily removed by a trimming or finishing die. The forward faces of the flanges, engaged by the outer pole plate structure, may be sufficiently trued by grinding 90 or equivalent operation. The width of the plate 9, of the outer pole plate structure O, between its opposite parallel sides 39, is substantially the width between the straight sides 38, 38 of the pot structure. The plates 9 95 may be stamped from material of that width, and the curved ends preferably conform with the curved flanges 7 of the pot.

Similarly, the inner plate 11, of the outer pole plate structure O, has parallel straight 100 sides 40, parallel to the straight sides 39 of the outer plate 9, and in general parallel to the straight sides 38, 38 of the pot. The plates 11 may be stamped from strip stock 105 of width indicated between the straight sides 40, 40.

Fig. 8 represents a strip of stock 41 from which are stamped circular pot blanks B1 in customary prior practice. It is evident that a considerable portion of the blank stock 41 is wasted, since all the area of the strip 41 between neighboring blanks B1 is waste, and in addition there is waste at the regions 42, due to the fact that satisfactorily to stamp 110 a circular blank from a strip, the blank must fall short on each side an amount equivalent to approximately the thickness of the stock.

In contrast, when using a rectangular blank B, Fig. 7, the waste in cutting blanks 115 from the stock is entirely eliminated. The difference in waste in the two cases is so substantial that by utilizing blocks B of the same weight as circular blanks B1, the thickness of the stock for the blanks B may be so much 120 greater, generally 50% thicker, with such resultant increase in thickness of the walls of the formed pot P that the magnetic reluctance of the circuit is so much lessened that 125 the amount of copper in the winding of the 130

field coil C may be materially reduced, in some cases to the order of one-third.

In drawing or forming pots from circular blanks B1, two forming operations are required, followed by a trimming operation. With rectangular blanks, such as B, but a single forming operation is necessary followed by the usual trimming operation.

By way of comparison, it may be stated that circular blanks B1, for a given pot structure, having a diameter of $8\frac{1}{4}$ inches, are stamped from stock $8\frac{1}{2}$ inches wide and about $\frac{1}{8}$ inch thick, while, in accordance with my invention for an equivalent structure, the blanks B1 may be 9 inches long and $5\frac{1}{4}$ wide and about 50% thicker than in the case of the blanks B1.

Because of suitable ratio of length to width of a blank B, there may be produced in a single operation a pot which is deep, as illustrated, or which may, if desirable, be even deeper. The pot in accordance with my invention is deep in the sense that it is as deep as pots heretofore drawn or formed from circular blanks as B1, in at least two operations. By recourse to a rectangular blank whose length is suitably great with respect to its width, a pot of practically any depth may be procured in a single operation. This results from the fact that during the first part of the relative movement of the die members with respect to each other, the effect is to draw or work the metal; while in the remainder of the movement the action is practically merely bending, forming or folding. In consequence, my pot may be described as one which is deep, whose bottom portion is characterized as drawn, and whose upper portion is characterized as merely formed.

The aforesaid advantages arise in the case where the pot structure as a whole is formed of a single pot element whose depth is relatively great, as approximately equal to or greater than its diameter, particularly when using a blank B considerably longer than its width. In a pot of this structure, the notch N is deep, and terminates at the open end of the pot at a level adjacent that of the air gap for the movable coil.

While, as indicated in Fig. 1, the leads from the field coil C may extend through the outer pole plate structure O, they may extend outwardly through one of the notches N in register with which, for the purpose, there may be a notch 9a in the outer pole plate 9, as indicated in Figs. 4 and 5.

While the pot P may have flanges 7, above described, they may be omitted, as indicated in Fig. 6, and the outer pole plate structure O may abut against the squared end 43 of the pot, and there held firmly, without recourse to a spacing ring or equivalent centering means, by bolts 44 passing through an extended bottom plate 4, and through the plate 9 and housing member 16.

What I claim is:

1. In telephonic apparatus of the character described, the combination with a pot, a central core and magnetizing winding, of outer pole plate structure comprising a plate secured to the pot, and a second plate secured to said plate on the inner side thereof, said plates having registering apertures forming with said central core an air gap, said inner plate terminating short of the wall of said pot.

2. In telephonic apparatus of the character described, a single pot element closed at its one end and open at the other, a field core disposed in said pot extending from its bottom and terminating approximately at its open end, a magnetizing winding on said core, notches formed in opposite sides of said pot element extending to its open end, and pole plate structure secured to the open end of said pot element between said notches, and having an aperture receiving said field core to form an air gap.

3. In telephonic apparatus of the character described, a single pot element closed at its one end and open at the other, a field core disposed in said pot extending from its bottom and terminating approximately at its open end, a magnetizing winding on said core, notches formed in opposite sides of said pot element extending to its open end, laterally turned flanges integral with said pot element at its open end between said notches, and pole plate structure secured to said flanges and having an aperture receiving said field core to form an air gap.

4. In telephonic apparatus of the character described, a single pot element closed at its one end and open at the other, a field core disposed in said pot extending from its bottom and terminating approximately at its open end, a magnetizing winding on said core, notches formed in opposite sides of said pot element extending to its open end, laterally turned flanges integral with said pot element at its open end between said notches, and pole plate structure secured to said flanges and having an aperture receiving said field core to form an air gap, said flanges and said pole plate structure having substantially coinciding parallel straight sides.

5. In telephonic apparatus of the character described, a pot element having flange structure at its open end, a field core disposed in said pot, a magnetizing winding on said core, and outer pole plate structure comprising a plate secured to the flange on said pot element, and an inner plate secured to said first named plate and terminating short of the wall of said pot element, said plates having registering apertures forming an air gap with said core.

6. In telephonic apparatus of the character described, a unitary pot-shaped casing of magnetizable material, a winding within said

- casing, a stud pole within said winding and secured in fixed position with respect to said casing, a single pole plate structure of magnetizable material engaging and adjustable upon the open end of said casing and having a central aperture forming with said stud pole an air gap, the relation of said aperture with respect to said stud pole depending solely upon the adjusted position of said single pole plate structure upon the end of said casing, and means for holding said pole plate structure in adjusted position in frictional engagement with the open end of said casing to prevent deformation of said air gap.
15. In telephonic apparatus of the character described, a unitary pot-shaped casing of magnetizable material, a winding within said casing, a stud pole within said winding and secured in fixed position with respect to said casing, a single pole plate structure of magnetizable material engaging and adjustable upon the open end of said casing and having a central aperture forming with said stud pole an air gap, the relation of said aperture with respect to said stud pole depending solely upon the adjusted position of said pole plate structure upon the end of said casing, means for holding said plate structure in adjusted position in frictional engagement with the open end of said casing to prevent deformation of said air gap, a diaphragm, and a voice coil attached to said diaphragm disposed in said air gap.
8. In telephonic apparatus of the character described, a single pot element closed at one end and open at the other, a field core disposed in said pot extending from its bottom and terminating approximately at its open end, a magnetizing winding on said core, notches formed in opposite sides of said pot element extending to its open end, pole plate structure having an aperture receiving said field core to form an air gap, and means for slidably securing said pole plate structure in frictional engagement with the open end of said pot element between said notches to prevent deformation of said air gap.
9. In telephonic apparatus of the character described, a single pot element closed at one end and open at the other, a field core disposed in said pot extending from its bottom and terminating approximately at its open end, a magnetizing winding on said core, laterally turned flange structure integral with said pot element at its open end, a single pole plate structure slidably engaging said flange structure and having an aperture receiving said field core to form an air gap, and means for securing said pole plate structure in frictional engagement with said flange structure to prevent deformation of said air gap.

RUSSELL T. KINGSFORD.
